UNITED STATES PATENT OFFICE.

OLIVER F. CLARK, OF ST. LOUIS, MISSOURI.

EGG-CARRIER.

SPECIFICATION forming part of Letters Patent No. 259,096, dated June 6, 1882.

Application filed March 1, 1882. (No model.)

To all whom it may concern:

Be it known that I, OLIVER F. CLARK, of the city of St. Louis, in the State of Missouri, have invented a certain new and useful Improvement in Egg-Carriers, of which the following is a full, clear, and exact description, reference being had to the accompanying drawings, forming part of this specification.

In the drawings, Figure 1 is a perspective view. Fig. 2 is a section with the upper portion of the cells removed. Fig. 3 is a section on line 3 3, Fig. 4. Fig. 4 is a section on line 4 4, Fig. 3.

A represents the carrier, and B the cells. The outside strips, a, are of the usual height, and are not divided. The cells B are divided horizontally at or near their middle, so that their upper portion can be removed, as shown, and for the purpose stated. The transverse strips of the upper half of the cells are held to-

gether by their interlocking in the usual way. The ends of the strips of the lower half of the cells, which also interlock in the usual manner, preferably extend through slots made in the outside strips, a, as shown. The bottom C is secured to the lower cells by means of thin strips c, of sheet metal. (See Figs. 1, 3, and 4.)

I claim as my invention—

The egg-carrier tray A, consisting of bottom C, cell part B, horizontally divided into upper and lower halves, sheet-metal strips c, securing the lower half of the cell part to the bottom, and the outside strips, a, the full height of the cell part, the upper half of the cell part being removable, as set forth.

OLIVER F. CLARK.
